(57) CLAIM

The ornamental design for a "hair claw," as shown and described.

DESCRIPTION

FIG. 1 is a perspective view of a hair claw, showing our new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof; and,

FIG. 8 is a perspective view of another embodiment of the hair claw.

The subject matter shown in dashed lines is for illustrative purposes and forms no part of the claimed design.
